UNITED STATES PATENT OFFICE.

JOHN L. C. HEINZ, OF CHICAGO, ILLINOIS.

HINGE WITH AUTOMATIC LIFTING AND LOCKING MEANS.

Application filed March 17, 1926. Serial No. 95,183.

My invention pertains to a hinge with automatic lifting and locking means, and has for its main object to provide a hinge which will enable a casement window to be lowered down behind the window stool, to make the window storm proof, and which hinge is provided with means acting automatically for locking said window in its closed position, and which is further provided with spring means for automatically lifting the window above the window stool when the window locking means has been released, so that the window may be readily swung and opened inwardly. Another object is to provide such a hinge with a slotted sleeve and with a plunger or means including a locking finger for locking said window in its closed position to prevent the same from being pried open from the outside.

Other objects and advantageous ends are attained with my invention, as will become apparent from the following description taken in connection with the accompanying drawings, in which,

Fig. 1 is an elevational view of a casement window in its closed position with my improved hinge applied thereto;

Fig. 2 is a vertical sectional view, taken along line 2-2 on Fig. 1;

Fig. 3 is an enlarged elevational view of the hinge mounted on a window, with the window in its open position;

Fig. 4 is a cross sectional view taken on line 4-4 of Fig. 3;

Figs. 5 and 6 are detail views of the two main parts of the hinge, separated or disassembled;

Fig. 7 is a detail view of the slotted sleeve for locking the hinge, and the guard member for the lifting spring, as shown in Fig. 3;

Fig. 8 is a cross sectional view of the locking plunger and connected hinge part, taken on line 8-8 of Fig. 5, and

Fig. 9 is a cross sectional view of a modified form of hinge in which the movable hinge part is mounted against the edge of the window.

In the drawings my improved hinge is illustrated in connection with a casement window including the window sashes 11 and 12, which, by the use of my improved hinges, are swingably mounted in the window frame 13, to engage inwardly of the transom 14 and to be movable downwardly

behind the window stool 15, thus preventing the rain from coming in under the casement window.

My improved hinge, as illustrated in these drawings, comprises two main parts 16 and 17, the part 16 being fastened to the frame 13 and having pintle barrels 18 adjacent its ends providing an extended space therebetween, while the part 17 has a pintle barrel 19 mounted to move between said barrels 18 and retained by means of a pintle 20 which may include a fixed head 21 and a removable head 22, as indicated in Figs. 3 and 5, the pintle barrel 19 being shorter than the distance between the pintle barrels 18, thus permitting the hinge part 17 to move longitudinally on the part 16 and on the pintle 20. The hinge part 17 in the preferred form includes a part 17' arranged substantially at right angles to the main part 17, thus permitting the main part 16 to be mounted on the inward side of the window frame while the part 17' is fastened on the inner face of the window sash, as shown in the drawings. The parts 16 and 17' are provided with suitable openings for receiving screws 23 to fasten the hinge parts on the window frame 13 and its finishing strip 24 and on the window sash, as indicated. The hinge part 17 with the attached window sash is movable along the pintle and the stationary hinge part 16 to lower the window outward of the window stool 15, and is movable upwardly to the upper part of the pintle to clear the window stool and enable the window to be swung inwardly over said stool.

Means is provided for locking the window with the attached hinge part 17 in its lowered or closed position, and this means is arranged to extend across the path of, and to engage, the movable hinge part 17 and hold it in its closed position. The construction of this locking means preferably includes a casing 25 fastened on or constructed integral with the stationary hinge part 16, and also includes a plunger 26 slidable in a chamber 27 in said casing and having a reduced end or stem 28 extending through a bore 27' in one end of the casing. The plunger has an integral curved finger 29 which rests against the pintle barrel 19 and has its end extending into a groove 17" in hinge part 17 when the window is lowered and a spring 30 on stem 28 automatically presses the plunger outwardly and presses the curved finger 29 against pintle 20 in the

path of and above the lowered pintle barrel 19, to lock the window in its closed position. A cross pin 31 on the plunger engages in a slot 32 in casing 25 and prevents the plunger and finger from rotating out of the proper position. A notch or bore is provided in the window frame 13 or in the sash strip 24 on said frame, for receiving the casing 25 and its plunger 26, substantially as shown in the drawings.

Means is also provided for automatically lifting the hinge part 17 with its attached window sash upwardly when the locking finger 29 with plunger 26 is withdrawn from its locking position, and this means preferably includes a coil spring 33 mounted on pintle 20 above the lower pintle barrel 18. This spring is of the required strength and tension to automatically lift the hinge part 17 with the attached window sash, as soon as the locking plunger and its curved finger are moved inwardly, thus releasing the pintle barrel 19. A guard member or sleeve 34 is mounted over spring 33 and is provided with an upper slot 35 for receiving the rib or flange portion 36 adjacent pintle barrel 19 of hinge part 17 when said hinge part with the attached window is moved downwardly into closed position. A slot 37 is provided at the lower end of sleeve 34 to receive the rib or flange portion 38 of hinge part 16, and this sleeve thereby provides means for positively locking the hinge part 17 against swinging movement on hinge part 16 when said part 17 is lowered and while the locking finger 29 extends above barrel 19 to hold it and the attached window in locked position. The slot 37 is slightly offset from slot 35 to properly accommodate the two flanged portions 36 and 38. A knurled nut 39 holds sleeve 34 in position, and any suitable turn-bolt 40 and locking member or eye 41 may be provided to fasten the window in closed position.

45 In the modified form shown in Fig. 9, a straight hinge part 47 is substituted for the angular hinge part 17 and 17' of the preferred form, thereby arranging and adapting this hinge to be fastened on the edge of 50 the window sash, as shown in said Fig. 9. The other parts of the hinge are exactly the same as in the preferred form, including a casing 25 with a plunger 26 and finger 29 thereon which has its end entering in a 55 groove 47' in the hinge part 47, while the window is open said finger engaging the pintle 20, and extending across the path of pintle barrel 49 on said hinge part when the window is closed, thus locking it in its 60 closed position.

It is apparent that the hinge part 17, aided by the weight of the attached window, may be readily pressed downward against the action of spring 33, and the attached 65 window may therewith be lowered into its

closed position to engage outwardly of the window stool 15, and that at the same time the spring 30 will automatically press the finger 29 into locking position to retain the window positively in its closed and locked 70 position, said hinge being furthermore retained in said locked position by the aid of sleeve 34 with its slots 35 and 37; and it is also apparent that by pressing the plunger 26 inwardly into casing 25, the spring 33 75 will automatically raise the hinge part 17 with the attached window to clear the window stool 15 and permit inward swinging of the window. This improved hinge is preferably used at the lower part of each 80 window sash only, while the locking finger and plunger and the surrounding sleeve are left off from the hinges at the upper part of the window sashes, although the spring 33 may be used with the upper hinges if 85 desired, thus enabling each sash to be readily opened by merely depressing one plunger with the finger.

What I claim as my invention and desire to secure by Letters Patent is:

90 1. A hinge comprising a part with spaced pintle barrels and a casing thereon, having a pocket with a slot, a second part with a pintle barrel movable between the spaced barrels longitudinally on said pintle, a 95 plunger provided with a spring in said pocket and with transverse means slidable in said slot to prevent rotation therein, said plunger having an integral finger to automatically move in the path of the pintle barrel on the movable hinge part for locking it in position, and a spring on said pintle to automatically move the movable pintle barrel out of such locked position when the locking finger is released.

100 2. A hinge comprising a part with spaced pintle barrels and with a casing integral therewith, a pintle in said barrels, another hinge part with a pintle barrel movable between the spaced barrels longitudinally on 105 said pintle, a spring on said pintle for automatically moving the movable barrel longitudinally on the pintle, a guard sleeve on said spring mounted against swinging movement on the first hinge part and having a 110 slot for receiving the second hinge part, and a plunger in said casing provided with a cross-pin to prevent rotation therein and having a locking finger to engage the second 115 pintle barrel and lock the second hinge part 120 in said slot.

125 3. A casement window hinge comprising a part fastenable on the window sash, and a second part fastenable on the window frame and including an integral casing set into a notch provided in said frame, the first hinge part having a pintle barrel and being movable with the window sash vertically on the second hinge part and frame, a plunger provided with transversely extending means 130

to prevent rotation in said casing and with
a curved finger for automatically moving in
the path of said pintle barrel to lock said
window in position, spring means for auto-
5 matically moving said window sash and at-
tached hinge part into open position on the
frame and other hinge part when said
plunger is depressed, and a spring in said
10 casing for automatically moving said plung-
er into locking position.

4. A casement window hinge comprising
a part fastenable on the window frame and
having an integral casing with a pocket and
a transverse slot to be set into said frame,
15 a plunger with a reduced stem and a spring
thereon mounted in said pocket and having
a pin movable in said slot to prevent rota-

tion of said plunger, spaced pintle barrels
on said hinge part, a second hinge part
fastenable on the window sash and having a 20
pintle barrel movable between said spaced
barrels, an integral curved locking finger on
said plunger to automatically move in the
path of said movable pintle barrel and lock
it with the window sash in closed position,
25 a spring for automatically raising said mov-
able window sash and hinge part when said
plunger is depressed, and a guard sleeve
around said spring and having slots for re-
ceiving said hinge parts and locking the 30
hinge and sash in closed position.

In testimony whereof I have signed my
name to this specification.

JOHN L. C. HEINZ.
